CLAIM

The ornamental design for an electronic device, as shown and described.

DESCRIPTION

FIG. 1 is a front view of an electronic device (e.g., a secure electronic data storage device or other electronic storage device) with a covering sleeve, showing our new design.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a top-front-right perspective view thereof.

FIG. 8 is a bottom-front-left perspective view thereof.

FIG. 9 is a bottom-rear-left perspective view thereof; and,

FIG. 10 is a top-rear-right perspective view thereof.

The shade lines show surface contour and not surface ornamentation.

BLUETOOTH® forming part of the claimed design is a registered trademark of Bluetooth SIG, Inc.
